MOMOTARO FUJII, OF TOKYO, JAPAN

THERAPEUTICAL INSTRUMENT

Application filed May 31, 1924, Serial No. 716,857, and in Japan June 15, 1923.

This invention relates to a therapeutical instrument consisting in a pressure-giving tube provided within an outer barrel, the said pressure-giving tube being actuated by a 5 spring, a bristle case containing a large number of bristles of flexible metal planted therein, actuated by a weak spring, the bristles being guided by small holes pierced through a guide plate, and a pressing head or knob provided at the upper extremity of the outer barrel. The object of this instrument is to treat disease by applying this instrument to the affected part and giving to that part a special pressure and stimulus, without giving pain or 15 causing bleeding.

The accompanying drawing shows an example of a convenient form embodying this invention, in which

Fig. 1 is a perspective view
20 Fig. 2 is a vertical section, except the bristle case, which is shown uncut,

Fig. 3 is also a vertical section, showing the mode of using my instrument, and

Fig. 4 is a perspective view of the bristle case, part being opened to show the internal structure.

The same reference character refers to the same or corresponding part throughout all the figures.

To explain my invention in detail with reference to the annexed drawing, to one end of an outer barrel (A) is screwed a guide tube (B), and between a shoulder (C) on the forward end of this guide tube (B), 30 which projects inward, and a pressing ring (D) fixed to the inner side of the outer barrel (A), is placed a pressure-giving tube (F) which has a shoulder (E) at its upper end, projecting outward, in such a way that while the instrument is not used, the shoulder (E) is in contact with the shoulder (C), the pressure-giving tube (F) being pressed to that position by a spring (G). To the upper end of the outer barrel (A) is screwed a pressing head or knob (H) which is in weight about two-thirds of the whole instrument. Within the barrel (A) is placed a bristle case (I) having its upper part enlarged as at (J). The bristle case (I) is so placed within the outer barrel (A) that its enlarged part lies

between the pressing ring (D) and the knob (H), and is pressed against the pressing ring (D) by a spring (K), while its lower part loosely passes through the pressing ring (D), the spring (G) and pressure-giving tube (F). 55 To the bristle case is screwed a seat (L) in which is planted a large number of bristles (M) of fine flexible metallic wire. These bristles are held in their proper position being loosely passed through small holes, one 60 bristle through one hole, of a guide plate (O) which is fixed to one end of a rod (N) firmly fixed at the other end to the seat (L).

To use my instrument, apply its lower end to any desired part (a) of the body and press 65 down the pressing knob. Then, as shown in Fig. 3, the inwardly projecting shoulder (C) being pushed down, thus disengaging the outwardly projecting shoulder (E), and the spring (G) being compressed by the pressing ring (D), the pressure-giving tube (F) will 70 be pressed against the body. At the same time, the pressing ring (D) being pushed down and freeing the enlarged part of the bristle case, the spring (K) will push down 75 the bristle case and the bristles will give desirable stimulus to the compressed part of the body. The bristles being of fine, flexible wires of metal, and being loosely passed through the small holes, and the spring which 80 presses the bristle case being weak, when they are pressed against the body, they are not strong enough to break through the skin, but will bend, giving only stimulus to the body. And as the instrument is provided with a 85 heavy head, it can be applied to the body vertically with steadiness when the head is pressed with the fingers. Thus the instrument can be applied to the body from several seconds to several minutes without causing 90 bleeding or giving any pain, except the special pressure and stimulus which is desirable.

Having now fully described this invention what I desire to have protected is

1. A therapeutical instrument comprising 95 a barrel, a yieldingly mounted bristle carrier carried thereby, and a plurality of relatively long flexible bristles mounted in said carrier.

2. A therapeutical instrument comprising 100

a barrel, a relatively long bristle carrier sliding in yielding relation thereto, said carrier having a plurality of long flexible bristles rigidly secured thereto at its inner end and
5 a guide near its outer end for holding the bristles in spaced relation, the bristles being freely movable longitudinally in said guide so as to be free to bend at their centers under an excess of pressure.

10 In testimony whereof I affix my signature.
MOMOTARO FUJII.
